UNITED STATES PATENT OFFICE.

FRANK A. BURNHAM, OF CLEVELAND, OHIO, ASSIGNOR TO THE CHANDLER & PRICE COMPANY, OF SAME PLACE.

PLATEN PRINTING-PRESS.

SPECIFICATION forming part of Letters Patent No. 624,452, dated May 9, 1899.

Application filed March 19, 1898. Serial No. 674,450. (No model.)

To all whom it may concern:

Be it known that I, FRANK A. BURNHAM, a citizen of the United States, residing at Cleveland, in the county of Cuyahoga and State of Ohio, have invented certain new and useful Improvements in Platen Printing-Presses; and I do declare that the following is a full, clear, and exact description of the invention, which will enable others skilled in the art to which it appertains to make and use the same.

My invention has reference to improvements in platen printing-presses; and the invention consists in mechanism for engaging and rotating the ink-distributing disk, all substantially as shown and described, and particularly pointed out in the claims.

In the accompanying drawings, Figure 1 is a side view of a press in which my invention is partially disclosed in elevation beneath the ink-disk. Fig. 2 is a plan view of the ink-disk with a portion broken away to disclose the engaging mechanism beneath the same. Fig. 3 is a cross-section of Fig. 2 substantially on line 3-3 on said figure. Fig. 4 is a plan view of the mechanism shown therein with a part of the bell-crank broken away and a part of the disk in section and showing the link which connects said crank and the said flange, with the ball-socket caps removed and with holes adjacent to the sockets for the cap-fastening screws.

A represents the main frame, and B the bed and its supporting members, pivoted below on the frame A.

C is the usual large gear at the side and top of the press, driven by the relatively small pinion D on shaft d, through which the power is applied to the press. The rod E connects gear-wheel C with the back shaft 40 G, on which the ink-roller frame is supported and adapted to rock.

Now it is desirable that the inking-disk H should be intermittently but regularly rotated part way around as the ink-rolls pass over it, so as to obtain a uniform distribution of ink on and by the ink-rolls h, and it is further desirable that this rotation of the inking-disk be effected with the least possible strain to the machine and with mechanism that will 50 be noiseless and out of the way. To these sev-

eral ends I support on the bearing-sleeve for the hub of disk H, Figs. 2 and 3, what is in this instance shown as a substantially flat arm L, which extends out practically as far as the said disk on one side of the machine, Fig. 4, and is 55 freely supported on the hub h of the disk, so as to rotate thereon and come back to starting position after each partial rotation of the disk without carrying back the disk itself. To make the necessary engagement with the 60 said disk to effect partial and intermittent rotation thereof, the disk itself is provided on its under side and some distance from its edge with a circular flange h' of such depth as to afford a bearing-surface for the engag- 65 ing mechanism. On the arm L, just outside of this flange and practically in constant touch therewith, is a segmental rib l and so constructed and positioned that pressure against the inside of flange h' by mechanism supported on said arm will lock the said flange and rib together, and thereby rotate the ink-disk. The engaging mechanism whereby this is accomplished consists of what may be termed a "cam-lever" m, pivoted on the arm L and 70 so constructed and arranged that when in one position its engaging portion contacts forcibly with the flange h' and locks itself thereon, as seen in Fig. 4, and when in the reverse position is disengaged and free from said flange, 75 as seen in Fig. 2. The said lever m makes such engagement with flange h' as to itself participate both in the locking engagement, which is completed on the other side by rib l, and in the forward movement of the ink- 80 disk.

Now in order to actuate the locking-lever m, as well as to release the same, I employ a bell-crank device N, having two arms n and n' and supported at their angle on a short 90 rock-shaft n². The arms n and n' are separated on this common axis n²—say as seen in Fig. 3—and are actuated through arm n', having a roller n⁴, running on the curved track or cam P, which is fixed on the rocking ink- 95 roller frame F. The construction and location of this track for roller n⁴ on arm n' are such that when the ink-rollers are carried up over the inking disk or plate H the arm n' will ride upon the higher surface of track P, 100

which is practically concentric with shaft G, and cause the arm n to keep cam-lever m in fixed position, and thus prevent the inking-disk from rotating when the ink-rollers are thereon. Then as the frame F oscillates in the opposite direction and the ink-rollers run down over the form on bed B the lever n' runs back to position seen in Fig. 1 and cam-lever m is actuated and the disk H is rotated. On the reverse oscillation of frame F the foregoing operations of disk H are again repeated, and so on continuously.

It will be noticed that by this construction of disk locking and actuating mechanism several advantages are obtained that are very material in the operation of the machine. In the first place the mechanism to do this work is removed from outside exposure and is simple and practically noiseless. These all are material considerations, as every practical printer knows. In the next place a thoroughly-effective locking engagement is made with the ink-disk H without bringing any strain or binding effect whatever on the bearing of said disk or on the arm L, by which it is actuated. In other words, the binding and the locking are both at the same place, between the rim or flange h', the rib l, and the cam-lever m, where they are needed and belong. This leaves both disk H and arm L perfectly free to be rotated and affords what I regard as an ideal mechanism and arrangement for this purpose.

Connection is made between the crank-lever arm n and the cam m by means of a single link O, having heads at its ends with semi-spherical sockets or cavities and carrying removable caps with corresponding cavities to engage the balls o' and o² on arm n and cam m, respectively. A screw-hole o³, Fig. 4, is provided at each end of link O for the screws to fasten said caps. The link O engages the cam-arm m at its long end, so as to obtain a strong leverage, and a pin or lug m' serves as a back-stop to the arm m. This furnishes a very simple, quiet, and positive actuation to the cam-arm m and makes it respond directly to every movement of the crank-levers n and n'. Especially does it afford a positive and prompt engagement of the inking-disk when such engagement occurs and also a prompt

release. However, in order that the return movement of lever L may be assisted and that a dragging release and engagement of the lock may be prevented I employ a coil-spring R, 55 supported at one end on the press-frame and engaged at the other with a lug on the hub of lever L. This helps to hold lever L back till positive engagement occurs by arm m and helps it back to normal position when released. 60 The crank-lever n has an enlarged head which carries roller n⁴, and this head serves as a counterweight to arm n' and the mechanism connected therewith to likewise promote prompt action of the cam m. When the reverse action occurs through bell-crank N after the cam-lever m has been engaged and operated in one direction, the said lever in its opposite movement strikes the pin or lug m' on arm L and causes said arm to move or travel 70 a limited distance with it, coöoperating with coil-spring R.

What I claim as new, and desire to secure by Letters Patent, is—

1. The inking-disk having a flange on its bottom, an arm pivoted on the hub of the disk having an upward projection to bear against the outside of said flange, in combination with a locking-cam pivoted on said arm to engage the inside of said flange and rotate the disk, 80 and a projection on said arm engaged by said cam in its reverse movement, a bell-crank and link to actuate said cam, and the ink-roller frame to actuate said bell-crank, substantially as described. 85

2. The mechanism for actuating the inking-disk, comprising a bell-crank and the oscillating frame and a cam thereon to operate the bell-crank, in combination with the inking-disk having a circular flange on its bottom, 90 a rotatable arm beneath said disk, a cam-lever pivoted on said arm and constructed to engage and lock on said circular flange and a link having pivotal connections with said lever and one part of the aforesaid bell-crank 95 lever, substantially as described.

Witness my hand to the foregoing specification this 4th day of March, 1898.

FRANK A. BURNHAM.
